UNITED STATES PATENT OFFICE.

JAMES B. MELLOY, OF PHILADELPHIA, PENNSYLVANIA.

BODY-WIRE AND HANDLE FOR DISH-PANS.

SPECIFICATION forming part of Letters Patent No. 377,632, dated February 7, 1888.

Application filed May 18, 1886. Serial No. 202,551. (No model.)

To all whom it may concern:

Be it known that I, JAMES B. MELLOY, a citizen of the United States, residing at Philadelphia, in the county of Philadelphia and State 5 of Pennsylvania, have invented certain new and useful Improvements in Combined Body-Wire and Handles for Dish-Pans and Similar Vessels; and I do hereby declare the following to be a full, clear, and exact description of the invention, reference being had to the accompanying drawings, which form part of this specification, in which—

Figure 1 is a perspective of combined body-wire and handles with strengthening-wires. 15 Fig. 2 is a perspective of combined body-wire and handles, and Fig. 3 is a plan of dish-pan having combined body-wire and handles and strengthening-wire applied thereto.

My invention has for its object to provide a 20 combined body-wire and handles for dish-pans and similar vessels.

My invention consists in the novel construction, combination, and arrangement of parts, hereinafter described and claimed.

25 Referring to the accompanying drawings, A represents a wire in the shape of a ring, which forms the body-wire for a dish-pan, B, and is applied to the latter, in the usual manner, by having the upper edge of the vessel turned 30 over it. Said body-wire is formed of lateral projections C C, of such shape and size as to answer for handles. These projections may be, as shown in Fig. 1, in the same plane as the ring; or they may have a slight elevation or 35 upward tendency, as shown in Fig. 2. In Fig. 1 the ends of the handles, or that portion of the wire which forms the ends, (designated by the letters c c,) are shown as parallel or ap-

proximately parallel, and the outer portion of the handle, or that which is grasped in lifting 40 the vessel, (designated by the letter c'), is being concentric or substantially concentric to the ring. In Fig. 2 the ends c' c' of the handles are curved, so as to cause the latter to widen as it recedes from the ring. 45

In some cases where dish-pans are made of several pieces, if the handle should straddle the seam between two of these pieces, a weakness might occur, to remedy which a supplemental wire (marked D) may be employed, 50 such wire being, in effect, a strengthening-wire or section of the body-wire located between the ends of the handles across the seam in the body and held in position by the edge of the vessel turned over it. 55

Before applying the body-wire to a dish-pan, notches should be made in the edge of the latter, as shown at d d, for the passage of the handles, or so as to permit the usual bead to be formed on the upper edge of the vessel without interference with said handles. 60

What I claim as my invention is—

The combination, with a dish-pan or similar sheet-metal vessel having a combined body-wire and handles, of a strengthening-wire, D, 65 located between the ends of the handles and held in place by the upper edge of the body of the vessel, substantially as shown and described.

In testimony that I claim the foregoing I 70 have hereunto set my hand this 13th day of May, 1886.

JAS. B. MELLOY.
